United States Patent Office

Des. 203,389

Patented Jan. 4, 1966

203,389

STEERING WHEEL

Rodger E. Geller, Dayton, Ohio, assignor to General Motors Corporation, Detroit, Mich., a corporation of Delaware

Original design applications Oct. 23, 1963, Ser. No. 77,115, now Design Patent No. 200,636, dated Mar. 23, 1965, and Oct. 1, 1964, Ser. No. 82,213. Divided and this application Jan. 26, 1965, Ser. No. 83,885

Term of patent 7 years

(Cl. D14—30)

The figure is a perspective view of a steering wheel showing my new design.

This is a division of parent applications Serial Nos. D-77,115 filed October 23, 1963, now Patent No. D-200,636 granted March 23, 1965, and D-82,213 filed October 1, 1964.

I claim:

The ornamental design for a steering wheel as shown and described.
